UNITED STATES PATENT OFFICE.

FRANCIS H. RICHARDS, OF SPRINGFIELD, MASS., ASSIGNOR OF ONE-HALF
TO THE PRATT & WHITNEY COMPANY, OF HARTFORD, CONN.

ENVELOPE-FOLDING MECHANISM.

SPECIFICATION forming part of Letters Patent No. 323,207, dated July 28, 1885.

Application filed April 30, 1884. (No model.)

To all whom it may concern:

Be it known that I, FRANCIS H. RICHARDS, a citizen of the United States, residing at Springfield, county of Hampden, and State of Massachusetts, have invented a new and useful Envelope-Folding Mechanism, of which the following is a specification, reference being had to the accompanying three sheets of drawings, forming a part thereof.

10 This invention relates to envelope-folding mechanism adapted to be used in connection with, and to form a part of, envelope-machines of the usual description, and is an improvement upon a similar invention for which Letters Patent of the United States No. 296,353 were granted to me, April 8, 1884, to which reference may be had.

15 The invention consists in certain combinations of mechanism, which will first be described in connection with the drawings, and then specifically pointed out in the claims.

Figure 1 is a side elevation of a part of an envelope-machine which has a folding mechanism embodying my invention. Fig. 2 is a 20 rear elevation of the same. Fig. 3 is a side view of certain parts of Fig. 2 in projection thereto. Fig. 4 is an enlarged view of a part of Fig. 2, the folding mechanism. Fig. 5 is an end elevation of, in projection to, Fig. 4. Fig. 6 is a sectional side elevation of the 25 folding mechanism in the same position as in Fig. 4. Fig. 7 is a sectional end elevation of the folding mechanism in the same position as in Fig. 5. Figs. 8, 9, 10, 11, 12, and 13 are views 30 of certain parts of the folding mechanism reduced to a simple form for illustrating their operation.

Similar letters refer to similar parts throughout the several views.

40 In the drawings, A is the frame-work of an envelope-machine of any construction suitable to carry the operative parts.

S is the driving or principal cam-shaft of the machine having the necessary pulley and 45 cams (not shown) for the usual operations of an envelope-machine, and, for the purposes of my present invention, the eccentric E, or its equivalent, cam C, and cam C'.

B is the pile of blanks, (see Fig. 1,) supported and fed to the pickers P in any convenient manner, as by table B', and between 50 guides B'.

O is an envelope-blank as taken up and held by the pickers, while the carriers K of the usual description are slid under it. P' is the usual guard-plate for separating the said blank from the pickers, which is done after the carriers are underneath it by raising the pickers, when the blank, coming in contact with said plate, is pulled off and falls onto the carriers, 55 which convey it to the proper position over the folding-box, into which box said blank is forced by the usual creasing-plunger P'. The carriers K are operated by links L from the lever L', which lever is pivoted upon rock-shaft S' and driven from cam C by means of a connecting-rod, R, which is provided with the usual cam-roller, (not lettered,) a spring, R', being employed to move the said rod in one direction, if desired.

70 The parts thus far described are or may be such as pertain to the envelope-machines in general use, and may be of any construction adapted to secure their proper operation.

The principal part of my improved folding 75 mechanism consists of a folding-box, D, Figs. 1 and 2, which is made double, and which is carried and adapted to be intermittently revolved upon and by shaft S'. This shaft is rotated through one-half of a revolution during the proper part of each complete revolution of cam-shaft S by means of any one of several suitable devices which are in use for similar purposes. In Figs. 1 and 2 I have 80 illustrated one such device, which consists of 85 the following parts: Gear G rigidly fixed on shaft S', gear G' revolving on stud S', ratchet-wheel G' rigidly secured to gear G', eccentric-rod R', which is driven by eccentric E, and has a pin, P', which operates the said ratchet, 90 and spring R' for keeping said pin in contact with said ratchet-wheel. The gear G' being twice the size of gear G, and the ratchet-wheel having four teeth, the eccentric E will obviously at each revolution turn the shaft S' one-half of a revolution. For preventing it from 95 going too far, if owing to its own momentum it should incline to do so, and to hold it in an exactly fixed position while at rest, said shaft S' may be provided with a stop-wheel, G', 100 which is acted upon by the stop-lever L', which lever is pivoted to the frame A at M, and operated by a suitably-formed cam, C', and spring R'.

The construction of the folding-box which I prefer to use is shown best in Figs. 4, 5, 6, and 7, wherein it is represented made of a central frame, D', which is rigidly fastened to shaft S², and two duplicate folding-boxes, D², secured to opposite sides of said frame. This frame is recessed at each end to make room for the concave cams N, which are fixed on tubes N', which tubes are themselves fixed 10 into the frame A.

Between the frame D' and the folding-boxes are formed bearings for the shafts of the end-folding wings W, back-flap-folding wing W', and seal-flap-folding wing W².

15 The several folding wings and cams N are substantially the same as in Patent No. 296,353, above referred to, except that in this case the box D revolves and the cams are stationary, while in that case the cams revolve and the 20 said box is stationary. In those Letters Patent the wings b and g, corresponding, respectively, to W' and W² of this application, are each operated by a separate cam. In this case they are operated each from a separate groove in the cam C'. The wing W', which requires the most power for its operation has a shaft, A', which terminates in a crank-pin in the inside groove, H, of said cam. The wing W² has a shaft, A², which is formed with a crooked 25 portion extending outside of the cam and terminating in a crank-pin in the outside groove, H', of said cam. These cam grooves, together with those in cams N, Fig. 4, are suitably formed to give the required movements to the 30 folding-wings, the wings W having arms A³ working in the grooves of cam N, substantially as shown herein and described in the said Letters Patent. Each box D², (see Figs. 4, 5, 6, and 7,) is provided with a movable folding-bed, 35 D³, and these two folding-beds are so connected together by slides I that when one is at the bottom of its box the other will be at the top of the opposite box. Friction-clamps I are provided to prevent the slides I from moving 40 too easily. A leather pad, I', is or may be provided under each folding-bed to prevent it striking the frame D' too heavily when driven down to the bottom of the box.

S¹ is the usual shaft for operating and carrying one end of the endless apron F, which may be of the usual construction and operated in the usual manner.

The operation of my improved envelope-folding mechanism is as follows: An envelope-blank, O, Fig. 1, is taken up from the pile of blanks B by the pickers P, transferred, as hereinbefore described, to the carriers K, which carry it to the proper position under the plunger P² and above the folding-box D, 55 which is held rigidly in the position shown. This position of the blank is shown also in Figs. 8 and 9. The two folding-boxes are distinguished from each other in Figs. 8, 9, 10, 11, 12, and 13 by the reference-letters D⁴, 60 and D⁵, respectively. When the blank reaches its position O in Figs. 8 and 9, which figures are similar to Figs. 7 and 6, respectively, the

folding-beds D³, being then in their upward position, as shown, the plunger P², descending upon the blank, acts to clamp it onto the folding-bed and to push it and said beds D³ down to their position, as shown in Figs. 10 and 11, and is then returned to its first position, leaving said blank partially folded at O'. The shaft S² and the folding-boxes are now, by any 70 suitable means, substantially as described, revolved (in this instance in the direction of the arrow) to their position in Fig. 12. During this movement, the form of the several cam-grooves being made suitable therefor, all the 75 several folding-wings of box D' are closed, of which W' and W² are so shown in said figure, folding said blank into a completed envelope, as at O², and upon continuing said rotation of said boxes to their position in Fig. 13, being 80 the reverse of that in Fig. 8, all of the said wings are opened to their positions, as shown in Figs. 8, 9, 10, and 11, leaving the beds D³ again in their uppermost position and the envelope at O³. The next downward movement of the plunger, acting through the beds D³, pushes the envelope down to the position O⁴, when it falls into a pocket of the endless apron at O⁵, after which it is disposed of in the usual manner. 90

I do not limit myself to two folding-boxes on shaft S², as any convenient number may be used, preferably two or four, so that their folding-beds may be connected as described.

Having thus described my invention, I 100 claim—

1. In an envelope-folding mechanism, the combination of fixed concave cams N, a revolving folding-box, substantially as described, and end-folding wings W, substantially as described. 105

2. In an envelope-folding mechanism, the combination of the fixed cam C', having cam-grooves H and H', a revolving folding-box, substantially as described, and side-folding wings W' or W², substantially as described. 110

3. In an envelope-folding mechanism, in combination, the fixed cams N and cam C' having cam grooves H and H', shaft S², and frame D', and a series of revolving folding-boxes, as 115 D², Figs. 4, 5, 6, and 7, each having wings W, W', and W², operated by said cams, substantially as described.

4. In an envelope-folding mechanism, in combination, a pair of revolving folding-boxes, 120 as D², folding-beds D³, connected together, and plunger P², substantially as described.

5. In an envelope-machine, in combination, suitable pickers, as P, a carrier, K, a plunger, P², and a series of intermittently-rotating folding-boxes, D², with their folding-wings and movable folding-beds, substantially as described. 125

FRANCIS H. RICHARDS.
